W. M. MILLIGAN

LUBRICATING SYSTEM FOR INTERNAL COMBUSTION ENGINES

Filed Nov. 8, 1922

FIG. 1

FIG. 2

FIG. 3

INVENTOR
WALKER M. MILLIGAN

BY

Pierre James
ATTORNEY

UNITED STATES PATENT OFFICE.

WALKER M. MILLIGAN, OF HUNTINGTON BEACH, CALIFORNIA.

LUBRICATING SYSTEM FOR INTERNAL-COMBUSTION ENGINES.

Application filed November 8, 1922. Serial No. 583,705.

To all whom it may concern:

Be it known that I, WALKER M. MILLIGAN, a citizen of the United States, residing at Huntington Beach, in the county of Orange and State of California, have invented certain new and useful Improvements in Lubricating Systems for Internal-Combustion Engines, of which the following is a specification.

10 The object of my invention is to provide improved devices for lubricating the stems of intake and exhaust valves of internal combustion engines.

15 Other objects and advantages of the invention will appear in the following description.

The invention consists in the novel construction, arrangement and combination of parts hereinafter described and claimed.

20 In the accompanying drawings,—

Figure 1 is a vertical sectional view of a portion of an internal combustion engine illustrating an embodiment of my invention to the valve mechanism. Fig. 2 is a perspective view of one of the complementary parts of the oil receiving cup. Fig. 3 is a plan view of the clasp-spring for retaining the cup members in coupled relations with each other.

25 In said drawing, the reference numeral 5 represents an intake or exhaust valve having a stem 6 passing through a guide 7 of an engine block 8 and into an adjustment attachment 9.

30 The adjustment 9 engages in a lifter rod 10 and is secured by means of a lock nut 11 engaging screw threads provided on the adjustment. The lifter rod 10 extends through a guide 12 and is elevated to effect the opening movements of the valve by means of a cam C in opposition to a valve closing spring 13 which is positioned between the guide 7 and a stop collar 14 provided on the valve stem 6.

35 The parts above described are of known construction.

According to the present invention the valve stem 6 is provided axially with a duct extending from a side outlet 15 within the guide 7 and communicates through ducts 16 and 17 of the adjustment 9 and lifter rod 10 with a groove 18 provided in the periphery of the latter.

36 19 represents a pipe through which oil is supplied under pressure into the groove 18

and thence is fed upwardly through said ducts and the outlet 15 to lubricate the valve stem with respect to the guide 7. 20 represents an aperture provided in the guide 7 at an elevation to register with the outlet 15 of the stem when the same is at or near its uppermost position for conducting oil into a groove 21 through which surplus oil escapes and flows downwardly and about the lower portion of the guide onto the peripheral surface of the valve stem.

The oil thus delivered upon the valve stem descends thereon through a hole 22 provided in the collar 14 and into a cup 23 which is seated upon a washer or collar 24 of felt or suitable packing which is seated upon the adjustment 9.

A helical spring 25 of less power than the valve closing spring 13 is employed below the stop collar 14 to retain the cup in its lowermost position on the stem. For the purpose of removing it from the stem, said cup is formed of two semicircular members 23¹ and 23² and are separably held together as by means of a clasp spring 26 extending circumferentially about the cup in a groove 27.

In operation oil supplied through the pipe 19 passes upwardly through the valve stem 6 and emitted through outlet 15 to lubricate the stem in the guide 7.

At or near the end of its upward strokes oil is delivered from said outlet into passage 20 whence it descends into the cup 23 to lubricate the lower portion of the stem through the medium of the felt washer 24.

The invention illustrated and described shows the same applied to one type of valve mechanism, but it may be applied to other types or arrangement of valve mechanisms.

What I claim, is,—

1. In an internal combustion engine, a valve stem provided with an axial duct having a side outlet, means for supplying oil into said duct, a guide surrounding said stem and having an opening affording communication between said outlet and the peripheral surface of the stem below said guide, and means provided on said stem for retaining the oil discharged through the guide opening.

2. In an internal combustion engine, a valve stem provided with an axial duct, a guide surrounding said stem, means for supplying oil into said duct, said stem being

provided in its periphery with an opening for delivery of oil from said duct to lubricate the interior of said guide, a two-part cup, and means for detachably connecting said cup to the stem below the guide for receiving surplus oil from the latter.

3. In an internal combustion engine, a valve-stem having therein an axially disposed duct and a discharge opening leading 10 to the stem guide of the engine to be lubricated, means for supplying oil into said duct, and means including an oil absorbent material for applying surplus oil from said guide to lubricate the valve stem exteriorly 15 of the stem guide.

4. In an internal combustion engine, the combination of a valve stem provided with an axially arranged duct having a side outlet, a lifter rod for said stem and provided 20 with a duct communicating with the duct of said stem, guides for the stem and the lifter rod, and means extending through the lifter-rod guide for supplying oil for lubricating the same and also to the stem

duct and the outlet thereof for lubricating 25 the stem guide.

5. In an internal combustion engine, the combination with the engine frame, of a valve, a stem therefor, a guide for said stem, said stem being provided with an axially arranged oil duct having a side outlet disposed within said guide, means for supplying oil through said duct and outlet to lubricate the stem bearing within the guide, an oil delivery way including in said guide 30 an aperture which is located to receive oil from said outlet when the stem is at or near the end of its valve opening stroke, a cup detachably connected to the stem below the guide, and an absorbent material applied to 35 the stem and in juxtaposed relations with said cup.

Signed at Huntington Beach, Calif., this 25th day of October, 1922.

WALKER M. MILLIGAN.
